STEPHEN FLAM, OF WALNUT PARK, CALIFORNIA.

MULTIPLE MOLD.

Application filed April 7, 1924. Serial No. 704,644.

This invention relates to a mold for casting blocks from plastic material and more particularly to a collapsible device providing a plurality of mold spaces, that may be quickly assembled and taken apart after the product is sufficiently set, for successive use. Ordinarily it is advantageous to lighten such blocks as much as possible, as by the aid of core holes, so as to save material and weight while yet maintaining the block of tile sufficiently resistent to all stresses imposed thereon. In such molds it has been customary to provide cores for each of the mold compartments, which remain associated with the mold until the product is entirely removed from the mold after setting. This treatment is especially necessary where free flowing material such as wet concrete is used for casting the block, 20 This type of construction therefore requires as many cores as are necessary to supply all the molds in use. Since the core itself is usually one of the most expensive parts of the mold, it is evident that the total cost 25 of the molding equipment is greatly increased by the provision of these numerous cores. It is one of the objects of my invention to obviate the necessity of using more than a relatively few cores. This I accomplish by using a mixture for molding that is sufficiently self-supporting to permit removal of the cores soon after pouring, and before the blocks are cured in a kiln or otherwise. In this manner, the same cores 30 can be used repeatedly even while the blocks are setting.

In the prior systems referred to, it is a laborious task to assemble all of the cores in a multiple mold, since each of them must 40 be handled individually. It is another object of my invention to save a large portion of the time formerly required to accomplish this result. I obtain this effect by providing for a simultaneous insertion and withdrawal of all the cores used in one complete 45 nest of molds.

It is another object of my invention to improve in general the construction of multiple molds.

It is still another object of my invention to make it possible to expose a very large surface of the block during the process of setting, to the action of the curing medium, such as steam, whereby a quicker set may be 55 obtained. This increased area is secured by

the pulling of the core before curing, which pulling exposes the sides of the cored holes to the curing medium.

My invention possesses many other advantages, which will become apparent as the description proceeds. The novel features of construction and operation upon which these advantages rest are set forth in the appended claims. The invention, however, may be best understood from a detailed description of one embodiment of my invention, illustrated in the accompanying drawings. Although but one embodiment is specifically described, it is evident that many other forms of my invention may be devised, 70 since the scope of the invention as defined in the claims is sufficient to cover many other forms.

Referring to the drawings:

Figure 1 is an end elevation of a mold 75 embodying my invention, shown with the cores in proper position for pouring, and a few of the parts in section, so as to expose the construction of the parts;

Fig. 2 is a side elevation of the mold of 80 Fig. 1, with some of the parts broken away, so as to permit the use of a large scale;

Fig. 3 is a top plan view of the apparatus, but with the cores and their supports omitted;

Fig. 4 is a detail sectional view, illustrating clearly the construction of the cores; and

Fig. 5 is a representation of a block that is produced by the apparatus shown in the preceding views.

The molding apparatus includes a flat table 11, shown most clearly in Fig. 2. This table forms the bottom of a plurality of mold spaces 12, and is supported in any appropriate fashion at a convenient height to permit ready handling. Since the blocks supported on element 11 must be cured, the arrangement is such that a hydraulic truck may be used to lift the entire mold and its 100 contents and to transport them to a suitable spot or kiln. To effect this result, a plurality of upright supports or legs 13 are mechanically connected to the plate 11, as by the aid of the channels 14, extending across and fastened to the ends of the plate 11. The supports 13 in the form of angle irons, are fastened to the rear of these channels, where they extend beyond the edges of plate 11. This is shown most clearly in Figs. 1 and 3. 110

In order to reinforce the plate 11, one or more stiffening channels 15 may be provided. Three are shown in the present instance, extending longitudinally of the plate 11, and the end ones being also connected to the legs 18. Furthermore, additional bracing such as struts 16 (Fig. 2) between legs 18 and the end channels 15 may be provided.

The foregoing description of the supporting means for the plate 11 is of course merely illustrative of a form that the support may take. The important feature is that a considerable space is provided immediately underneath the plate 11, for accommodating a plural core structure, as well as the truck that is used for transferring the mold from place to place.

Upon the plate 11 there rest a number of separating plates 17, which assist in forming the mold spaces 12. In Fig. 3 the plurality of spaces is shown as arranged in a double column, each extending longitudinally of plate 11, but of course other arrangements may also be used. To support these plates 17 in proper position, a central partition 18 is provided, formed of a pair of longitudinal spaced plates 19, and fastened to the plate 11. These plates have slots 20 which accommodate projections or tabs 21 formed at the sides of the separating plates 17. In order to retain the tabs in place and prevent removal of the plates, rods or wires 22 are provided, extending through the series of tabs 21 and within the partition 18. The separating plates 17, being once assembled with respect to partition 18, need not be at any time dismantled or withdrawn from position; this is due to the fact that only two columns of molds are provided, and therefore it is entirely feasible to slide the finished product off at the longitudinal edges of the plate 11 even while plates 17 are in place. The remaining sides of the mold spaces 12 are formed by the aid of the longitudinal plates 23, one on each side of the bottom plate 11. These plates also have slots into which tabs or projections 24 extend, formed on the separating plates 17. These longitudinal plates 23 are purposely made long enough to provide space for some form of tighteners to keep these plates in position. In the present instance I show hooks 25 for accomplishing this result, which hooks extend between the partition plates 19 and the longitudinal plates 23. This manner of holding the plates 17 is not only simple, but also conveniently and quickly detachable. For permitting cores of appropriate form to enter the mold spaces 12 from below, one or more apertures 26 are provided for each space, in the plate 11. In the present instance two apertures and therefore two cores for each mold space, are shown.

As many of the table structures just de-

scribed are used as desired, the number being dependent upon the capacity of the plant. On the other hand, only a few nests of cores need be provided for the entire plant, since the cores are arranged to be withdrawn from the molds soon after pouring, and used again for a succeeding series of molds. The nest of cores and one form of operating mechanism therefor are most clearly shown in Figs. 1 and 2; and in Fig. 4 the construction of one of the cores is clearly indicated. The individual cores 27 are in proper place for molding in Fig. 1, while in Fig. 2 they are withdrawn from the mold spaces. The cores 27 are preferably made hollow, either cast or stamped, and have a configuration that corresponds with the shape of the apertures 26; in this instance, a frustum of a square pyramid with rounded edges.

In order to support these cores 27 in proper spaced relation so that all of them can be moved simultaneously into and out of the mold spaces 12, I provide a vertically movable structure, including a series of horizontally extending channel irons 28. Four of these irons are shown in the present instance, corresponding to the four longitudinal rows of apertures 26 in plate 11, and each supporting a row of cores 27. To facilitate the manipulation of the fastening bolts or rivets 29 (Fig. 4) which pass through the internal flanges 30 of the cores, I leave a portion of each core wall open near the bottom, as shown at 31. Furthermore, the taper of the cores is made gradual, so that a sufficiently tight fit can easily be secured between these cores and the apertures 26.

The channels 28 are rigidly fastened at their ends to the horizontal legs of angle irons 32. The vertical legs extend upwardly and cover the ends of the channels. These irons and the channels 28 form a gridiron-like structure. This structure is made vertically movable in any appropriate fashion, so as to project the cores 27 at will into the spaces 12, or to withdraw them as required. This function may be accomplished, for example, by fastening other angles 33 to the horizontal leg of angle 32, and supporting the vertically apertured guides 34 thereon. These guides may be in sliding engagement with the stationary vertical rods 35. Grease cups 36 may if desired be provided for reducing the friction between rods 35 and guides 34. In the present instance I show four rods 35—one near each corner of the gridiron-like structure.

The stationary support for the rods 35 is formed in any appropriate manner, as for instance, by the standard structural iron sections. Thus I show two end supports 37 of channel iron having horizontal portions 38 and two leg portions. These channel

shapes are narrow enough to permit them to pass between the upright legs 13, as clearly shown in Fig. 1; and the horizontal portions 38 are high enough to permit the entry underneath it of a wheeled truck body, the sides of which are diagrammatically indicated at 39. After the molds and cores are all assembled and the molds filled, this truck is used to lift the entire 0 mold off the ground 40 by engaging the lower surface of the horizontal portion 38, and urging these portions upwardly. Then by permitting the truck body to drop, and in addition lowering the cores, as described 5 hereinafter, the nest of cores may be withdrawn by the truck from beneath plate 11 and reinserted under an unfilled mold structure; the operation of filling and removal of the cores may thus be repeated 10 again and again, using the same nest of cores.

Continuing with the description of the supports for the vertical guide rods 35, the horizontal portions 38 of supports 37 are joined by a rectangular frame 41, formed of channel sections and provided if necessary with horizontal stays 42. Also stay rods 43 running crosswise and connecting the vertical portions of supports 37 are preferably added, to lend rigidity to the structure. Near the corners of frame 41, the rods 35 are securely anchored therein. The tops of the rods 35 are furthermore held rigidly in proper spaced relation by the use of a flat plate 44 that is fastened as by bolts 45 to the rods 35. These plates also serve to protect the operating mechanism for raising and lowering the cores, from the drip from the molds or the mixer. For this purpose the plates 44 have forwardly curved portions that serve readily to shed the liquid or semiliquid matter falling thereon.

The mechanism for raising and lowering the cores 27 may take any of several mechanical devices. For illustration, I have chosen one that is simple and inexpensive to manufacture. It comprises a pair of stationary racks 46, one supported at each end of the frame 41, and also held rigidly in place by the aid of the top plate 44. Engaging with each of the racks 46 there is a pinion 47, fastened to a shaft 48 supported rotatably from the core structure; for this purpose the straps 49, fastened appropriately to the central channels 28, carry the bearing blocks, 50, in which the shaft 48 is journaled. This shaft is of course long enough to extend entirely from end to end of the core frame, and at one end, it is provided with a squared portion 51 to accommodate a wrench or crank. It is evident that by rotating the shaft 48 in the proper direction, the channel frame carrying the cores 27 may be made to move

vertically on guide rods 35. In order to keep the cores 27 in the upper position of Fig. 1, a pawl 52 is provided, which engages one of the pinions 47, preferably that which is adjacent the handle end of shaft 48. 70 This pawl is shown as pivoted on the angle iron 33 and weighted so as to urge the pawl into engagement with the teeth of the pinion 47.

The structural features of my invention 75 have now been described. Its mode of operation, although elucidated in connection with the description of structure, may appropriately be summarized at this point. First of all, the separating plates 17 are 80 properly assembled with respect to the partition 18; then the longitudinal plates 23 are put in position and held by the aid of hooks 25. Then a truck carrying a nest of cores 27 in lowered position, is passed under 85 the table 11, and positioned so as to align the cores 27 with the apertures 26. The shaft 48 is rotated to raise the cores to the position of Fig. 1, the guide 34 sliding over the rods 35. When the cores are in raised 90 position, the pawl 52 holds the channel gridiron frame in its upper position. The truck with its load of mold and cores may now be positioned for filling. After this is accomplished the truck is wheeled to a 95 drying kiln or other locality, the cores lowered to the position of Fig. 2; this movement also permits the legs 13 to rest on the ground, since up to this point these legs were lifted by the movement of cores 27 into the apertures 26. When these legs 13 again rest on the floor, the truck with the cores 27 may be taken out from under the plate 11, and reinserted under an empty 100 nest of molds. The mixture for molding 105 is of course such that the blocks are sufficiently self-supporting to permit the core removal. The product is shown in Fig. 5.

Due to the fact that the cores are withdrawn right after casting, the curing is hastened, there being a large exposed area for the curing medium to act on the blocks. Only two or three nests of cores 27 need be 110 provided, for they can be used over and over again with any number of multiple molds. After the blocks are sufficiently cured, it is 115 a very simple matter to remove them. For this purpose, only the plates 23 need be 120 taken off; the blocks can then be slid off sidewise from the molds. The reassembly of the molds is therefore very quickly accomplished, especially since all of the cores are inserted simultaneously and as quickly with- 125 drawn. All of these features assist very materially in speeding up the molding process, as well as reducing the cost of mold construction. Furthermore, since the cores are pulled out of the cast blocks downwardly, there is no tendency when pulling these 130

cores to distort the block in any way. This feature renders it practicable to remove the cores very shortly after the blocks are cast.

I claim:

5. 1. In a mold for casting material, means forming a plurality of molding spaces, each having apertures in the bottom, a plurality of cores arranged to be projected through the apertures, a common, vertically movable support for the cores, and means whereby said cores serve as a sole support for all of the molds.

10 2. In a mold for casting material, a flat horizontal plate having apertures, means co-
15 operating with said plate to form a plurality of mold spaces, a supporting structure for the plate, and means forming cores for the mold spaces, comprising a vertically movable support, and cores carried thereby, said
20 support and cores being movable to a position beneath the plate.

25 3. In a multiple mold for casting material, a bottom plate, a stationary partition fastened to the plate, separating plates an-
chored to the partition plate, said separating plates extending on each side of the partition, and a pair of removable plates, one on each side of the partition, with which the separating plates cooperate to form the
30 mold spaces, there being only two rows of mold spaces, one on each side of the stationary partition.

35 4. In a multiple mold for casting material, a plate forming the bottom of the mold, a partition fastened to the plate for forming the common wall between the two rows of mold spaces, said two rows being the only rows in the mold, separating plates arranged at right angles to the partition and having
40 projections entering into slots formed in the partition, means for anchoring said separating plates against withdrawal, and a pair of removable plates parallel to but spaced from

the partition, cooperating with the separating plates to form the two rows of mold spaces.

5. In a multiple mold for casting material, a pair of independent supporting structures, means for a plurality of mold spaces supported by one of said structures, said mold spaces having apertured bottoms, and a plurality of cores arranged to be projected through the apertures into the spaces, and supported on the other of said structures.

6. In a multiple mold for casting mate-
rial, a flat plate having a plurality of aper-
tures, a plurality of spaced legs for sup-
porting said plate at a distance above the
ground, a movable support arranged to be
placed beneath the plate, a frame vertically
movable and carried by said support, and a
plurality of cores supported by said frame
and arranged to be projected through the
apertures of the plate.

7. In a process for manufacturing molded articles having cored apertures, by the aid of a mold having a bottom apertured plate, and cores arranged to be passed through the apertures, which comprises filling the mold with the cores in active position, transport-
ing both the mold and the cores to a curing
space, lowering the cores so as to permit the
mold to rest on appropriate supports, and
removing the core structure from the curing
space.

8. In combination, a portable mold structure, an independently portable core structure, said mold structure having apertures in the bottom through which the cores can extend vertically, and means for raising and lowering the core structure, said core structure serving as a temporary support for the mold structure during molding.

In testimony whereof, I have hereunto set
my hand.

STEPHEN FLAM.

cores to distort the block in any way. This feature renders it practicable to remove the cores very shortly after the blocks are cast.

I claim:

5. 1. In a mold for casting material, means forming a plurality of molding spaces, each having apertures in the bottom, a plurality of cores arranged to be projected through the apertures, a common, vertically movable support for the cores, and means whereby said cores serve as a sole support for all of the molds.

10. 2. In a mold for casting material, a flat horizontal plate having apertures, means cooperating with said plate to form a plurality of mold spaces, a supporting structure for the plate, and means forming cores for the mold spaces, comprising a vertically movable support, and cores carried thereby, said 15 support and cores being movable to a position beneath the plate.

15. 3. In a multiple mold for casting material, a bottom plate, a stationary partition fastened to the plate, separating plates anchored to the partition plate, said separating plates extending on each side of the partition, and a pair of removable plates, one on each side of the partition, with which the separating plates cooperate to form the 20 mold spaces, there being only two rows of mold spaces, one on each side of the stationary partition.

25. 4. In a multiple mold for casting material, a plate forming the bottom of the mold, a partition fastened to the plate for forming the common wall between the two rows of mold spaces, said two rows being the only rows in the mold, separating plates arranged at right angles to the partition and having 30 projections entering into slots formed in the partition, means for anchoring said separating plates against withdrawal, and a pair of removable plates parallel to but spaced from

the partition, cooperating with the separating plates to form the two rows of mold 40 spaces.

5. In a multiple mold for casting material, a pair of independent supporting structures, means for a plurality of mold spaces supported by one of said structures, said 50 mold spaces having apertured bottoms, and a plurality of cores arranged to be projected through the apertures into the spaces, and supported on the other of said structures.

6. In a multiple mold for casting material, a flat plate having a plurality of apertures, a plurality of spaced legs for supporting said plate at a distance above the ground, a movable support arranged to be placed beneath the plate, a frame vertically 60 movable and carried by said support, and a plurality of cores supported by said frame and arranged to be projected through the apertures of the plate.

7. In a process for manufacturing molded 65 articles having cored apertures, by the aid of a mold having a bottom apertured plate, and cores arranged to be passed through the apertures, which comprises filling the mold with the cores in active position, transporting both the mold and the cores to a curing 70 space, lowering the cores so as to permit the mold to rest on appropriate supports, and removing the core structure from the curing space.

8. In combination, a portable mold structure, an independently portable core structure, said mold structure having apertures in the bottom through which the cores can 75 extend vertically, and means for raising and lowering the core structure, said core structure serving as a temporary support for the mold structure during molding.

In testimony whereof, I have hereunto set my hand.

STEPHEN FLAM.

Certificate of Correction.

It is hereby certified that in Letters Patent No. 1,585,845, granted May 25, 1926, upon the application of Stephen Flam, of Walnut Park, California, for an improvement in "Multiple Molds," errors appear in the printed specification requiring correction as follows: Page 1, line 19, for the word "block" read *blocks*; page 2, line 2, after the word "provided" strike out the comma and insert a period; page 4, line 36, claim 4, after the word "between" strike out the article "the"; same page, line 49, claim 5, for the word "for" read *forming*; and that the said Letters Patent should be read with these corrections therein that the same may conform to the record of the case in the Patent Office.

Signed and sealed this 29th day of June, A. D. 1926.
